FIG. 3

UNITED STATES PATENT OFFICE.

WILLIAM F. PHARE, OF BIRMINGHAM, ALABAMA.

APPARATUS FOR MANUFACTURING ARTIFICIAL ICE.

Application filed May 24, 1927. Serial No. 193,850.

My invention relates to a raw water ice freezing system of the stationary can type.

The objects of my invention are to lower the cost or original installation of artificial ice manufacturing plants; simplify by standardization the manufacture, shipment and replacement of equipment and stock materials; reduce the cost of chemicals; reduce the freezing time for 300 lb. blocks to save from 14 to 18 hours; quicken the thawing time without requiring extra water or steam for that purpose; reduce the refrigerating losses due to exposure of cold surfaces; more adequately protect the air and water lines from freezing; and obtain great flexibility in filling the cans, removing and replacing their core water and harvesting the finished ice. All of the above advantages are obtained in addition to the known advantages of the stationary can systems, such as their labor economy; group system filling, thawing and core removal; and automatic float control of the can water levels.

The most important feature of my invention is concerned with the construction of the can and the circulation of the brine thereabout. According to my present invention the can is seated in a jacket surrounding its sides and extending under its bottom, and through the space thus provided I circulate brine at high velocity, utilizing valve controlled headers so that the brine can be returned either through the brine cooler or through coils in the fore cooler where the exchange of heat and cold will warm the re-circulated brine sufficiently to thaw the ice and at the same time to cool the incoming can water. In my arrangement I eliminate the necessity of large brine storage capacity and my improved method of circulating the brine provides for the lowest possible freezing and thawing time because of the absolute exposure of practically the entire can surface to a circulation of cold or warm brine traveling at high velocity.

A further distinctive feature of my invention lies in the fact that the inner or freezing cans are connected to the water laterals at the bottom center only, sufficient insulation surrounding the water pipe to prevent freezing

of the latter by the brine in the jacket and to cause a small pocket to form at the bottom of the ice block in place of the protruding lug of ice now generally produced, thereby avoiding the necessity of removing such lug before the block can be stood on end.

A further important feature of my invention lies in the fact that the inner or freezing can can be readily detached and removed from its jacket without disturbing the brine and water circulating connections to the latter or the air and water connection to the can itself, thereby reducing maintenance cost and simplifying the labor and expense of freezing can replacement.

Another distinctive feature of my invention lies in the utilization of the single supply water connection to serve both for the core water removal and for the introduction of air coming from suitable air laterals.

A further distinctive feature relates to the manner of insulating all cold surfaces, and to this end the jacketed cans are surrounded with proper insulation which extends under their bottoms and protects the air and water connections from freezing and effectively insulates the brine headers and laterals. By this arrangement a very large economy in plant construction can be obtained because there is no necessity for heavy or expensive supports for the cans and all tank construction is eliminated.

Another distinctive feature of my can construction lies in the fact that the inner or freezing can is detachably connected to the jacket by a readily accessible joint at the top and at the bottom is free of connections except to the water header, which connection is made by a nipple readily removable from the top of the can, thereby simplifying to the maximum degree the removal and replacement of the ice cans.

My invention further comprises the novel details of construction and arrangements of parts, which, in their preferred embodiment only are illustrated in the accompanying drawings which form a part of this specification, and in which:—

Fig. 1 is a plan view of a typical group of stationary cans omitting the insulation.

and showing the piping system laid out in the manner suitable for a ready understanding of the operation of the system.

Fig. 2 is an enlarged cross-section through a can taken on the line II—II of Fig. 1.

Fig. 3 is a view taken on the line III—III of Fig. 1, with the can shown partly broken away.

Similar reference numerals refer to similar parts throughout the drawings.

In the embodiment of my invention illustrated, I show a group of cans comprising the inner freezing cans 5 and the outer jackets 6 which are arranged in groups and surrounded by suitable insulation 7 (see Fig. 2) about the sides and insulation 8 under the bottom of the cans and between the stringers or beams 9 which support the weight of the cans and in turn rest upon any desired foundation, not shown.

The cans are all of like structure and are each provided with a wide top flange 10 which overlaps a shorter outturned top flange 11 at the top of the jacket 6. A packing 12 is interposed between the flanges 10 and 11 which are connected together by bolts 13 or equivalent readily demountable fasteners. The inner can is of such size as to provide between it and its jacket a brine space 14 extending entirely about the sides and under the bottom of the can. A disk 15 of suitable insulating material, such as asphalt, is interposed in the center of this bottom brine space and is provided with a central aperture for the passing therethrough of the water nozzle 16 which passes through the jacket and through the bottom of the can 5 and there receives a removable nipple 17 which connects the bottom of the can to the nozzle. The nozzle is provided with a shoulder 18 which engages the under-surface of the bottom of the jacket in such position that by tightening up on the nipple 17 the can and jacket can be drawn tightly against the insulation disk 15 as a packing to effectively seal all joints against leakage. The nipple 17 is provided with tool sockets 19 adapted to receive a long handle tool by means of which it can be unscrewed from the work floor, thereby permitting the can 5 to be readily lifted out of the jacket and as readily replaced, it being only necessary to remove the attaching bolts 13 which are also readily accessible from the work floor. By this arrangement the cans can be assembled with and removed from their stationary jackets for interchange or replacement with the greatest ease and facility. The insulating disk 15 is of sufficient width and blocks off enough of the brine space at the center of the bottom of the can to accomplish two purposes, namely, to safe guard the water nozzle from becoming frozen and to maintain a central unfrozen pocket of water at the bottom of the ice block, which is desirable for

facilitating the removal and replacement of core water and the circulation of air.

The brine, which term I use for any available refrigerant, for freezing or thawing is supplied to the cans from a brine header 20 which is laid in the bottom insulation 8 and has laterals 21 leading to each side through the insulation and through the can supports 8 to each side of the several cans at the center thereof, as will be seen more clearly in Fig.

70 75

1. There the laterals are provided with suitable elbows 22 and connections 23 opening through the bottom of the jacket on opposite sides of the insulation disk 15. These connections may be provided with removable

so 80

nipples 17^a, similar to 17, and likewise adapted to be unscrewed from above should it be desired to disconnect the jacket from the brine inlet connections. The brine return header 24 is provided with laterals 25 extending alongside the can jackets to the middle

85

thereof and there provided with angled connections 26 which enter the top portion of the brine space on opposite sides of the center. This header and the laterals 25 are also suitably enclosed within the insulation 7 and protected thereby.

90

Cold brine is supplied to the header 20 under control of valve 27 from a pipe line 28 in which is included the motor driven pump 29, the brine cooler 30 and a return pipe 31 comprising a valve 32 and connected to one end of the return header 24.

95

The return header 24 at its other end, under control of a valve 33, is connected to a pipe 34 which includes a motor driven pump 35, a coil 36 in the fore cooler 37, and a return pipe line 38 comprising a valve 39 and connected to the header 20. During the freezing

100

operation, the valves 33 and 39 are closed, the valves 27 and 32 are opened and the pump will thereupon force a circulation of brine from the cooler 30 through the header 20, laterals 21 through the brine space 14 in the several cans and out through the laterals 25 and return header 24 past valve 32 and

105

through the pipe line 31 to the cooler 30, thence returning in the same cycle. A relatively small quantity of brine can with this arrangement be forced at high velocity to travel through the brine spaces in the jacketed cans while protected throughout its circulating system with efficient insulation, and it is capable of producing a very rapid freezing so that the ice in 300 lb. blocks can be made

110

within from 26 to 30 hours without difficulty.

115

When it is desired to harvest the ice the valves 27 and 32 are closed, the valves 33 and 39 are opened, whereupon warm brine will flow from the line 38 past valve 39 through the header 20 and laterals 21 and up through the brine spaces 14 in the several cans, returning through laterals 25 and header 24 past valve 33 and the pump 35 to the fore cooler 37, where it serves to prechill the water supply for the cans and in doing

120 125 130

so becomes sufficiently heated to adapt it to rapidly thaw the ice blocks for harvesting.

The water system in my apparatus comprises a pipe connection 40 leading from the fore cooler 37 to a supply tank 41 into which which water flows under the control of a valve 42 responsive to a float 43 which is set and adapted to maintain the water level in the tank 41 at the proper level for the water 10 in the cans. This will be seen more clearly in Fig. 3. A water supply line 44 leads from the bottom of the tank 41 past an overflow 45 with its open top level with the predetermined water level for the cans and then continues past the control valve 46 to a water header 47 which has cross connections 48 and 49 at the end of each series of cans or elsewhere which connect it with a parallel header 50. The headers 47 and 50 run along the 20 outside of the cans in each group and are provided with laterals 51 which lead inwardly through the insulation 8 to the center of each can and are there provided with elbows 52 by means of which each connects to its respective water nozzle 16. The header 47 beyond the connection 49 therewith leads past a valve 53 to a suction pump 54 driven by a motor 55 and adapted to discharge the core water through a discharge pipe 56. In operating the water system, the valve 46 is opened to admit raw water to flow through the laterals 51 and fill the tanks to the level controlled by the float 43 in the tank 41 and by the overflow 45 the valve 53 being closed during the filling operation. When it is desired to draw the core water, the valve 46 is closed, the valve 53 is opened and the pump 54 started, which will rapidly suck out and discharge the core water, whereupon this can be replaced by again closing the valve 53 and opening the valve 46. Preferably the piping system will be arranged for juxtaposition of the valves 46 and 53.

My invention contemplates the use of low pressure air though obviously high pressure air may be used if desired. I show the air supply pipe 57 for a group of cans having a control valve 58 and having air headers 59 and 60 on opposite sides of the cans which are respectively connected by laterals 61 leading through the insulation 8 and supports 9 and connected into the water nozzles 16 as a preferred manner of introducing air in the cans. By so introducing the air I avoid a separate air connection to the cans. The air will, in a manner well understood, continuously bubble up through the water and ice block core and the air pipes will be amply protected from freezing by the insulation 8. It will be noted that both the air and water laterals 61 and 51 are removed as far as possible from and preferably disposed on opposite ends of the can from the brine supply laterals 22. This is important as an arrangement for re-

ducing to a minimum the chance of freezing either the water or air connections.

It will be obvious that my system is capable of being operated with very great facility and flexibility and that by using the same 70 headers and laterals for the distribution of both hot and cold brine I obtain maximum simplicity in construction and lowest possible cost of erection and maintenance of the apparatus. My methods for the removal and 75 replacement of the core water eliminates most of the labor incident to the manufacture of ice and the very rapid circulation which can be induced will enable me to operate the system with a very small quantity of brine 80 at high efficiency.

Having thus described my invention, what I claim as new and desire to secure by Letters Patent, is:—

1. In an ice making machine, a freezing unit comprising an outer brine containing jacket, a water can fitted into the jacket to provide a common bottom and side brine space, means connected to the jacket to circulate brine through said space, an insulation filler occupying the center of the bottom brine space, a water nozzle leading through the jacket and filler to the can, and a nipple removable from above for connecting the can to the nozzle.

2. In an ice making machine, a freezing unit comprising a brine containing jacket open overhead, a water can detachably connected overhead to the jacket and spaced throughout its sides and bottom therefrom, a disk of insulating packing filling the space between the can and jacket bottoms, a water inlet for the can which is surrounded by said disk between can and jacket, said inlet comprising a top and a screw nipple adapted to tighten the can and jacket walls against the packing disk, and brine circulating connections for the jacket.

3. In an ice making apparatus, a plurality of jacketed freezing cans, manifold brine supply and return circulation connections to the can jackets, manifold bottom water connections to the cans, and insulation under and around the cans and between the brine and water connections.

4. An ice making apparatus according to claim 3, in which the brine supply connections for a can enter its jacket at the sides of the bottom thereof and the water connection leads to the center of the can bottom 120 in spaced relation to the brine connections.

5. In an ice making apparatus, a plurality of jacketed freezing cans, manifold brine supply and return circulation connections to the can jackets, manifold bottom water connections to the cans, insulation under and around the cans and between the brine and water connections, supports under the cans, brine circulating connections leading through the supports and insulation to the can jackets,

and water supply pipes leading beneath the supports and bottom insulation and passing the latter upwardly in spaced relation to the brine pipes into the cans.

5 6. In a stationary can apparatus for making ice, a group of jacketed cans, means to circulate brine through the can jackets, a brine cooler, a fore cooler, means to direct the brine circulation through the brine cooler 10 or the fore cooler, a water supply tank, valve controlled inlet manifold connections to the group of cans, means to supply chilled water to the tank from the fore cooler and maintain it therein at the level desired for the 15 cans, and a valve controlled outlet connection leading from the inlet manifold connections to a group to discharge the core water.

7. An ice freezing apparatus comprising 20 a group of stationary jacketed freezing cans, surrounded by insulation and each having a brine space surrounding its sides and extending under all but the center of its bottom, an insulating disk occupying the brine space 25 beneath each can, top and bottom brine circulation connections leading through the insulation to the can jackets, and air and water manifold supply circuits leading to the center of the can bottoms through the insulating 30 disk and protected thereby from freezing and valve controlled means for withdrawing core slush through the water manifold supply circuit.

8. A freezing can having a flat bottom and 35 an outturned top marginal flange, a flat bottom can jacket also having a top flange, bolts connecting the can and jacket flanges and assembling same to provide a shallow brine space entirely enclosing the side and bottom 40 walls of the can, a water nozzle projecting centrally through the jacket and can bottoms, a nipple screwed on the nozzle, and a compressible body of insulation surrounding the nozzle and adapted to be compressed by said 45 nipple between the bottoms of the can and jacket to pack the nozzle openings and insulate the nozzle.

9. In an ice making apparatus, a plurality 50 of freezing cans each having an opening in the bottom thereof, means for circulating brine around the cans, water and air manifold connections to the openings in the bottoms of the cans, means for supplying water to and withdrawing core slush from the cans 55 through the water manifold, and valve means to control the supply of air through the air manifold connections.

In testimony whereof I affix my signature.
